FLUID IMPELLER STRUCTURE

Alfred T. Gregory, Massapequa, N. Y., and Kenneth A. Browne, Lakewood, Ohio, assignors to Fairchild Engine and Airplane Corporation, Farmingdale, N. Y., a corporation of Maryland

Original application October 27, 1950, Serial No. 192,440. Divided and this application January 17, 1952, Serial No. 266,815

5 Claims. (Cl. 230—120)

This invention relates to fluid impeller structures, and has particular reference to impellers for gas turbines utilized for the propulsion of aircraft, although the invention is not limited thereto. This is a division of application Serial No. 192,440 filed October 27, 1950.

Gas turbine engines usually have been designed to meet primarily the requirements for performance and long operating life rather than for production in large quantities and for a relatively short operating life. In consequence gas turbine engines including the impeller and turbine, contain many castings and large forgings and require a great number of man-hours of labor for their production.

In accordance with the present invention, an impeller for a gas turbine engine is provided, and which permits the use of the specialized high-production stamping, rolling, forming and drawing machinery presently used and available in the automotive and allied industries for the fabrication of its parts as well as automatic welding apparatus for joining the parts for a major portion of the engine.

In a preferred embodiment of the invention, the impeller consists of stamped sheet metal blades that are butt-welded to a hub member, which is supported at its front end by the forward or thrust bearing and which carries a rear flange to which is secured the front end of the turbine shaft whose rear end is attached to the turbine which is journalled in the rear main bearing.

The impeller blades are rigidly braced to each other by segments which form the inner surfaces of the impeller air passages and which are welded or brazed both to the impeller blades and at their rear edges to a disc covering the rear of the impeller, this disc also being welded to the impeller flange and preferably to the rear edges of the impeller blades. The high velocity compressed air is discharged from the impeller through an annular diffuser formed by the outer casing, an inner wall and contoured vanes all welded together.

It will be seen that the present invention provides a light-weight and efficient impeller for a gas turbine engine that can be manufactured in high volume production at low cost with standard and available fabrication methods and machinery.

For a more complete understanding of the invention, reference may be had to the accompanying drawings, in which:

Fig. 1 is a front view of the gas turbine engine embodying the impeller of this invention and, shown partly in section as seen along the lines 1A—1A of Fig. 2, and 1B—1B of Fig. 3; and

Figs. 2 and 3 in numerical order from left to right, jointly constitute an axial section through the impeller portion of the gas turbine engine, as seen along the line 2—2 of Fig. 1, and being shown broken away to expose parts in the interest of clarity.

Referring to the drawings, numeral 1 designates the tubular outer casing formed and shaped of sheet ma-

2

terial by a drawing process in large hydraulic presses and then the seams will be automatically welded at the proper stage in the fabricating operations.

Encircling casing shell 1 is a mounting flange 13, which is welded completely around and to casing shell 1 at joints 14. Flange 13 comprises the only means necessary for supporting the engine on an aircraft or other mount, since the tubular casing formed by the joined shell 1 constitutes a very rigid cantilever support for the entire engine so that no added stiffening or supporting means is required.

Numerical 3 designates the impeller hub which has axial surface ridges 3', forming a fluted surface as shown in Fig. 1, and preferably comprises a solid forging to finished dimensions, except where a minimum of machining may be necessary to control the fitting of adjoining parts. As shown especially in Figs. 1, 2 and 3, the sheet metal impeller blades 4 are flash butt-welded to the ridges 3' of the impeller hub 3 along joints 5 and extend radially outwardly, with their outer edges conforming to the contour of casing shell 1 although spaced therefrom.

The impeller blades taper in thickness radially outwardly as shown in Fig. 1, and are spaced and secured together by web-like face segments 6 stamped and formed from relatively thin sheet metal and having narrow flanges 6a at their edges. These web segments form the inner wall of the impeller air passages and the edge flanges 6a are automatically roll-welded, spot-welded or brazed to the blades 4 along their edges 7. The segments 6 have a parabolic or arcuate cross section contoured to limit centrifugal stress in the material.

Numerical 8 designates a flanged ring having a forwardly projecting axial flange 9 slotted to fit blades 4 which are welded thereto. The rearward edges of blades 4 are welded to disc 10 along their abutting surfaces. The rear ends of face segments 6 are flanged at 6a to facilitate their being welded to disc 10 at joints 12. Thus the entire impeller is rigid and strong, and the space within face segments 6 and disc 10 is completely enclosed to minimize windage losses.

The forward end of impeller hub 3 is journalled in bearing 23 mounted in gear case 21 which is supported centrally in the open front end of casing 1 by airfoil section struts 20, several of which, such as four, are used for that purpose, as shown in Figs. 1 and 2. Struts 20 preferably are formed from sheet metal material and are welded at their ends to casing 1 and to gear case 21, which likewise is fabricated from two shells 21a and 21b of sheet material of different thicknesses, the thicker or tubular shell 21b serving as the support for the bearing 23, as shown in Fig. 2.

A bevel pinion 24 secured to the forward end of impeller hub 3 in gear case 21, drives bevel gear 25 and radial shaft 26, which extends through the casing 1 into externally-mounted accessory gear box 22. Gear box 22 contains gearing and an oil pump and has provision for mounting the various accessories to be driven from hub 3.

Referring particularly to Fig. 3, numeral 15 designates the large diameter, tubular turbine shaft, preferably formed by rolling a steel sheet into a tube and flash butt-welding the seam. The impeller attaching flange 17 is flash butt-welded to the forward end of tubular turbine shaft 15 and is fabricated from sheet steel by punching to size and stamping to shape. As shown in Figs. 1 and 3, the rear flanged ring 8 on impeller blades 4 is bolted at 11 to the front flange 17 of the tubular turbine shaft 15, which carries the turbine, not shown.

The high velocity air from the impeller travels along the inner surface of casing 1 through the annular space 4' formed between the casing 1 and an inner, substantially tubular wall 6' secured to the casing 1 by airfoil-

shaped diffuser vanes 7' welded to casing 1 and wall 6', as shown in Figs. 1 and 3. The forward end of the tubular inner wall 6' lies coextensively and in axial alignment with the rear end of the impeller face segments 6, so that the air can flow smoothly without turbulence from the impeller into annular space 4'. Similarly, the rearward end of the inner wall 6' converges toward the axis of the turbine shaft 15. The flow of air diverging in that direction is aided by annular deflector 5', which is welded to the interior surface of casing 1, as is shown especially in Fig. 3. The annular stream of compressed air flowing between the deflecting and guiding surfaces 5' and 6' enters the combustion chambers or burners, not shown.

Proper functioning of the engine and high speed rotating parts, including the impeller and the turbine, requires satisfactory balancing of these parts. This is readily accomplished according to the invention without expensive machining operations by slotted sheet metal balance ring 48 secured to the front end of turbine shaft 15 as is shown in Figs. 1 and 3. In order to achieve the desired balance of the rotor assembly, the peripheral teeth or spokes formed on balance ring 48 by the slots are simply broken off at the points indicated by balancing apparatus as being in unbalance.

Operation of the gas turbine impeller of this invention will be readily understood from the foregoing description of the construction thereof, and although a preferred embodiment of the invention has been illustrated and described herein, it is to be understood that the invention is not limited thereby or thereto, but is susceptible of changes in form and detail within the scope of the appended claims.

We claim:

1. In a gas turbine engine, the combination of a hollow compressor casing, a rotor hub journalled therein, substantially radial blades having elongated inner edges secured to said hub, outer rearwardly diverging edges substantially complementary to the shape of the casing and leading and trailing edges, and web segments connected to and interposed between successive blades and extending substantially the axial length of said blades, said web segments diverging outwardly relative to the axis of said hub from the inner ends of the leading edges of the blades adjacent the hub to points adjacent to but spaced inwardly from the outer ends of the trailing edges of said blades thereby forming a hollow core supporting said blades and closed in the direction of the leading edges of the blades and flaring rearwardly and outwardly toward said casing.

2. The gas turbine engine set forth in claim 1, comprising a substantially tubular wall mounted in axial alignment with said webs within said casing to form an annular space therewith.

3. The gas turbine engine set forth in claim 1, comprising a substantially tubular wall mounted in substantial alignment with said web segments within said casing and forming an annular air passage therewith, and diffuser vanes extending substantially radially across said air passage and spaced apart angularly around said annular air passage.

4. In a gas turbine engine, the combination of a hollow compressor casing, a rotor hub journalled therein, longitudinal ridges on said hub, substantially radial blades having elongated inner edges secured to the outer edges of corresponding ridges, said blades having narrow leading edges, wider trailing edges and rearwardly diverging outer edges adjacent and complementary to said casing, webs connected to and interposed between successive blades and extending substantially the axial length of said blades, said web segments diverging outwardly relative to the axis of said hub from the inner ends of the leading edges of the blades adjacent the hub to points adjacent to but spaced inwardly from the outer ends of the trailing edges of said blades, and means extending substantially radially inwardly from the axial ends of said webs to the hub to enclose the space within said webs against windage and form a hollow core having an outer and reinforcing periphery joined to the blades at about their middles.

5. In a gas turbine engine, the combination of a hollow casing, a rotor hub journalled therein, longitudinal ridges on said hub, substantially radial blades secured along their inner edges to the outer edges of said ridges, each blade also having a leading edge, a trailing edge and an outer edge complementary to at least a portion of the interior of said casing, said trailing edge being longer than the leading edge and the outer edge being inclined relative to the inner edge, and webs connecting successive blades in circular alignment, said webs extending from about the junction of said inner and leading edges to the rear edge inwardly of but adjacent to the junction of the outer and trailing edges to form an annular surface flaring outwardly from the inlet edges of the blades to their outer edges and being reversely curved in longitudinal section.
